[54] CLOSED CIRCUIT TELEVISION CAMERA
FOR USE IN DISPLAYING GRAPHIC
MATERIAL OR THE LIKE[76] Inventor: Takashi Mikami, 11-36 Morino
4-Chome, Machida-shi, Tokyo,
Japan[] Term: 14 Years[21] Appl. No.: 819,585[22] Filed: Jul. 27, 1977[51] Int. Cl. .... D14—03[52] U.S. Cl. .... D14/78[58] Field of Search D14/1, 52, 72, 79, 84, D14/99; 358/231, 250, 254, 94, 229

[56] References Cited

U.S. PATENT DOCUMENTS

D. 168,004 10/1952 Teuber D14/79
D. 213,300 2/1969 Buck D14/84

1,889,576	11/1932	Snook	358/94 X
3,816,646	6/1974	Cinque	358/94 X
3,819,855	6/1974	Rush et al.	358/229 X

Primary Examiner—Joel StearmanAssistant Examiner—Jane E. CorriganAttorney, Agent, or Firm—Edward H. Loveman

[57] CLAIM

The ornamental design of a closed circuit television camera for use in displaying graphic material or the like, substantially as shown and described.

DESCRIPTION

FIG. 1 is a front elevational view of a closed circuit television camera for use in displaying graphic material or the like showing my new design;

FIG. 2 is a left side elevational view;

FIG. 3 is a right side elevational view;

FIG. 4 is a top plan view;

FIG. 5 is a rear elevational view; and

FIG. 6 is a bottom plan view.

Fig. 1

Fig. 2

Fig. 3

Fig. 4

Fig. 5

Fig. 6